UNITED STATES PATENT OFFICE

JOHN F. BARGHAUSEN, OF WASHINGTON, DISTRICT OF COLUMBIA, DEDICATED BY ASSIGNMENT TO THE GOVERNMENT AND THE PEOPLE OF THE UNITED STATES OF AMERICA

APPARATUS FOR BRANDING THE GRADE ON CHEESE

Application filed February 20, 1930. Serial No. 430,004.

(GRANTED UNDER THE ACT OF MARCH 3, 1883, AS AMENDED APRIL 30, 1928; 370 O. G. 757)

This application is made under the act approved April 30, 1928, and the invention herein described, if patented, may be manufactured and used by or for the Government for governmental purposes without payment to me of any royalty thereon.

I hereby dedicate the invention herein described to the free use of the public, to take effect upon the granting of a patent to me.

10 My invention relates to a branding apparatus of general application but the primary function of which is to mark, imprint, or brand suitable legends on the top or bottom surface of cheese that has been paraffined and placed in cold storage to age. Without such identifying mark the average person who is lacking in experience in classifying cheese would be unable to determine the quality of the cheese.

20 One of the principles of the invention is to provide an improved device of the class just referred to, whereby the marking fluid may be evenly spread upon the irregular surface and deep into the paraffin and at the same time reflow the paraffin over the ink branded letters, which is necessary to preserve the cheese from mildewing. Another object is to provide ready means for regulating the feed of the marking fluid to the deep cut

25 metal letter sector by means of inked rollers. Another object is to provide a revolving brush that makes contact with the deep cut metal letter sector and removes all of the paraffin or other matter that may congregate in the letters, and which tend to clog such letters, the brush being positioned in such a manner as to clean the metal letters before they are inked. A still further object is to provide a device of the class described that

30 is simple in construction, easy to operate, efficient in service and so constructed to insure the branding of the cheese even though it may have an uneven surface.

In the accompanying drawings, Figure 1

35 is a perspective view of the entire apparatus; Figure 2, a detailed view of the circular branding carriage; Figures 3 and 4, a perspective view of the revolving carriage.

Similar numerals refer to similar parts throughout the views.

Referring to the drawings, it will be seen that from bed or base 1, on which is mounted a pipe support forming an arm 2, in which a housing 3 is fastened in the outer end 4 to serve as a bearing for perpendicular hollow shaft 5 which carries the circular branding carriage 6. This carriage bed 6 is cast aluminum so formed with recess 7 to accept a circular heating unit 8 which is connected to terminal 9 which receives the electrical energy for heating unit. On the bottom side of carriage 6 the deep cut metal letter sector units 10 describing the grade are fastened to carriage 6 by means of four steel capped pins 11 which passes through the carriage bed 6 through holes 12 that are counter bored on top and bottom 13. These steel pins 11 are threaded on the end 14 and are fastened to sector units 10. There is a small compression spring 15 that pin 11 passes through and sets 70 between carriage 6 and sector units 10. By this method the branding surface adjusts itself to any irregular surface of cheese when brought in contact with the surface of cheese.

At the top of hollow shaft 5 there is located a handle 16, which is used to bring the circular branding carriage 6 down to the cheese surface. On arm 2 there is also connected a metal brace formation 17, which is fastened on arm 2 at point 18, also on housing 3 by the means of screws, which forms a support for a pulley 19 at the top and over hollow shaft 5. There is also an opening in arm 2 at point 20 where a pulley 21 is located by the means of a shaft 22 on which a chain 23 passes over pulleys 21 and 19 and through hollow shaft 5, to swivel pin 24, this chain carries counter weight 25 on one end and branding carriage 6 on the other end. This method permits hollow shaft 5 on which branding carriage 6 is fastened by means of two set screws 26 to turn two-thirds of its circumference on swivel pin 24.

There is a stationary shaft 27 located on bed 1 at point 28 on which there is a revolving carriage 29 on which there is assembled a revolving brush 30 and two felt friction rollers 31 and 32. The operation of this revolving carriage 29 and brush 30 are as follows: $\frac{1}{8}$ H. P. motor 33 located on bed 1 by 100

the means of a V belt 34 to a grooved pulley 35, which is attached to a fifty to one reducing gear 36. On one end of shaft 37 of reducing gear 36 there is a bevel gear 38 which meshes with bevel gear 39, which is fastened to the carriage 29. On bed 1 there is fastened a metal brace 40 that forms a bearing 41 for other end of shaft 37 of reducing gear 36. On shaft 37 there is a bevel gear 42 which meshes with gear 43 on shaft 44. On the upper end of shaft 44 there is a sprocket wheel 45 on which there is a chain belt 46 which is connected to sprocket wheel 47 which is fastened to a bevel gear 48, which in turn meshes with bevel gear 49 on revolving brush 30 which is located on revolving carriage 29. When motor 33 is in motion it revolves grooved pulley 35 of reducing gear 36 which revolves shaft 37 which in turn revolves bevel gear 38 which revolves carriage 29 by means of meshing with gear 39. When shaft 37 revolves, bevel gear 42 meshes with bevel gear 43, revolves shaft 44 which in turn revolves sprocket wheel 45 on which is chain belt 46, which is attached to sprocket 47 on stationary shaft 27.

Bevel gear 48 is attached to sprocket wheel 47 which in turn meshes with bevel gear 49 which revolves brush 30 on revolving carriage 29, when revolving carriage 29 is in motion.

On bed 1 there is a platform 50 on which is a circular sub-platform 51 located under carriage 6. This sub-platform 51 is set on four tension springs 52 pivoted in center 53, which allows sub-platform 51 to parallel itself to that surface of the cheese to be branded.

Located under arm 2 there is a metal lever rod 54 which is pivoted at 55 on brace 56 which has a metal stirrup 57 pivoted at point 58, which operates spring electric switch 59. Lever rod 54 extends to perpendicular shaft 5 and is supported by brace 60. When operator presses down on handle 16 located on shaft 5 this lever rod 54 breaks the electric contact on switch 59, which automatically breaks electric connections which stops the revolving carriage 29 and brush 30. When handle 16 on shaft 5 is released by operator the said shaft 5 on which branding carriage 6 is fastened moves upward automatically and presses against end of lever rod 61 which, through the medium of leverage pressing down on stirrup 57, automatically stops all revolving parts. When revolving carriage 29 is in operation the branding carriage 6 is always up to its highest point. The revolving brush 30 on carriage 29 passes under and cleans all the branding sectors 10 on carriage 6; also places the ink on branding sector 10, by means of two felt friction rollers 31 and 32 in rear of brush 30. Collar with set screw 62 above carriage 6 on shaft 5 adjusts the height desired for branding carriage 6. On metal support 63 there is an idler pulley

64 which regulates the pressure on chain belt 46, an adjustable metal brace 65 which supports arm 2 from stationary shaft 27, fastening nut 66 for brace 65.

I claim:

A machine of the character described comprising a base, an upright hollow shaft supported by said base, a horizontal hollow arm attached to said hollow shaft, a branding device having metal letters supported by said hollow arm, means for heating the branding device, said branding device being adapted to embedding legends in paraffin surfaces, a stationary vertical shaft attached to said base, a carriage so positioned as to revolve around said stationary vertical shaft, means to revolve said carriage, a rotatable brush attached to said carriage, means to positively rotate said brush and means whereby said branding device will adjust itself to any irregular surfaces when brought in contact therewith.

JOHN F. BARGHAUSEN.
